UNITED STATES PATENT OFFICE.

IWAN OSTAFIJCHUK, OF FORT WILLIAM, ONTARIO, CANADA.

COMBINATION ARTICLE OF FURNITURE.

1,381,134.

Specification of Letters Patent. Patented June 14, 1921.

Application filed August 9, 1920. Serial No. 402,500.

To all whom it may concern:

Be it known that I, IWAN OSTAFIJCHUK, a citizen of Poland, residing at Fort William, in the district of Thunder Bay and Province of Ontario, Canada, have invented certain new and useful Improvements in Combination Articles of Furniture, of which the following is a specification.

This invention relates to improvements in combination articles of furniture, and the objects of the invention are to provide an article of furniture which can be used as a chair, or be converted into a table, or converted into a bed.

It is also the object of this invention to adapt the upholstering of the chair as a mattress for the bed, and when converting the chair into a bed to permit of it being simultaneously extended longitudinally and laterally.

Many other objects will become apparent as the invention is described more fully in the following specification.

So that the nature of the invention may be more clearly understood, I have illustrated an embodiment thereof, which I shall now describe, after which the novel features of the invention will be pointed out in the appended claims.

In the drawings: Figure 1 is a perspective view of my invention when used as a chair.

Fig. 2 is a perspective view of the chair upholstering removed and extended to form a mattress.

Fig. 3 is a plan view of the frame of the article of furniture extended to form a bed, a part being broken away to show the connection of the endless chain with the rods which are connected to the ends of the bed or sides of the chair.

Fig. 4 is a perspective view of my improved device when used as a bed.

Fig. 5 is a perspective view of the chair with the ornamental superstructure rotated about its hinged edge, to allow the table top to rest thereon.

Fig. 6 is a plan view of the underside of the table top. Similar symbols indicate corresponding parts in the several drawings.

In carrying out my invention I employ a rectangular frame 1 of skeleton formation, the side members 2, and the front and rear transverse members 3 and 4 being formed as guides as illustrated in Fig. 3.

Slidably mounted in the front and rear transverse members 3 and 4 are rods 5 and 6,

to which the side walls 7 of the chair are attached, these side walls being designed to form the end walls of the bed.

In the front member 3, rods 8 are also slidably mounted and are attached at their outer ends to the side walls 7. The back of the chair is formed of two sectional walls 9 which are hinged to the side walls 7, and when these sectional walls are open, they lie in the same plane as the walls 7 and constitute therewith the ends of the bed.

A transverse bar 10 is located adjacent to the transverse member 4, and this bar is connected to bars 11 which are slidably mounted in the side members 2 of the frame of the chair.

The bottom portion 12 of the side walls 7 is extensible and is connected to the bars 13 which are slidably mounted in the bar 10.

It is advisable when converting the chair into a bed that the sides 7 of the chair, and the back should be simultaneously actuated and extended, and for this purpose, I provide a pair of spindles 14 and 15, which are journaled in the sleeves 16 and 17, and a pair of transversely extending spindles 18 and 19 which are journaled in the sleeves 16 and 17.

The spindles 14 and 15 are provided with sprockets with which the chains 20 engage, and the spindles 18 and 19 are provided with sprockets with which the chains 21 engage.

The chains 20 are connected by plates 22 with the rods 5 and 6, and the bars 11 are connected by a transverse member 23, which is attached to the chains 21.

The spindles 14 and 18 are provided with intermeshing gears 24 and 25 and the spindle 14 extends through the front of the frame and is provided with a squared end 26, with which the key 27 engages.

When the spindle 14 is rotated by the key 27, the rods 5 and 6 and the bars 11 will be moved laterally and rearwardly of the chair, and when the back wall 9 of the chair is rotated outwardly, then the bed frame illustrated in Fig. 3 is set up.

The upholstering 28 of the chair is formed in six rectangular sections, secured together as shown in Fig. 2, that is to say, the seat 29 is hingedly connected to the sides 30, and the back 31 is connected to the seat 29.

The sections 32 are not attached to the back 31, but are attached to the sides 30. When these sections are laid out to lie in

the same plane, they will form the mattress of a bed, but when used as the upholstering of a chair, then the back 31 is rotated to a right angle, relatively to the seat 29, and the sides 30 are then rotated to a right angle relatively to the seat 29, and the sections 32 fold in behind the back 31, and this seat sides and back are then placed on the frame 1 with the sides engaging the walls 7 and 10 the back 31, and sections 32 engaging the back 9 of the chair.

On the top of the side walls 7, ornamental superstructure 33 is hingedly connected, and on the back wall 9, ornamental superstructure 34 is also hingedly connected.

If the chair is to be converted into a table, then the ornamental superstructure 33 and 34 is rotated to lie along the outer faces of the walls 7 and the back 9, and the upper 20 edge of the walls 7 have orifices 35 therein exposed.

The table top 36 is formed in two sections hingedly connected, and these sections when opened out are held in the same plane 25 by a movable bolt 37.

On the under face of the table, dowel pins 38 are provided to engage with the orifices 35 in the side walls 7, and the under face of the table has recesses 39 which give 30 clearance to the hinges on the tops of the side members 7 and the back 9, and so prevent the table top from wobbling.

When the table top 36 is not in use, it is folded up and stored at the side of the 35 chair.

The back walls 9 of the chair, will be held in locked position by a catch 40.

When this combination article of furniture is being used, it will when assembled as 40 a chair, have the appearance illustrated in Fig. 1. To convert the chair into a bed it is only necessary to remove the upholstering 28, loosen the catch 40 and engage the key 27 with the squared end 26 of the spindle 14.

45 The key 27 should now be rotated, to rotate the spindle 14, which will through the gears 24 and 25, rotate the spindle 18. The chains 20 and 21 will now be operated, and the side walls 7 will be moved outwardly from the frame 1, and simultaneously the 50 member 10 will be moved rearwardly of the said frame.

When the side members 7 have been fully extended, and also the member 10, then the 55 back wall 9 of the chair will be rotated into alignment with the walls 7, so completing the frame of the bed.

The upholstering 28 is now laid out flat, and placed on the frame of the bed as shown 60 in Fig. 4.

If the article is to be used as a table, then

the bed is reconstructed into a chair, and the ornamental superstructure 33 and 34 is rotated about its hinged edges to lie along the outer face of the side walls and back 7 and 9.

65 The table top 36 is now extended and locked in this position by the bolt 37, and the top is then superposed on the chair and the dowel pins 38 engaged with the orifices 35.

70 This combination article of furniture is very compact, and can be readily converted to the several uses above described.

What I claim as my invention is:

1. A combination article of furniture 75 comprising a side frame, side members, a sectional back hinged to the side members, the bottoms of said side members being telescopic, bars slidably mounted in the transverse member of the frame and connected 80 to said telescopic members, and means for simultaneously moving the side members and the transverse member to form a bed frame.

2. A combination article of furniture 85 comprising a side frame, side members, a sectional back hinged to the side members, the bottoms of said side members being telescopic, bars slidably mounted in the transverse member of the frame and connected 90 to said telescopic members, means for simultaneously moving the side members and the transverse member to form a bed frame, a removable sectional upholstering serving 95 when the device is used as a chair and adapted to be flattened out to form a mattress when the device is used as a bed.

3. A combination article of furniture comprising a frame, side members, a sectional back member hinged to the side members, a transverse member, rods slidably mounted in the frame attached to the side members, bars slidably mounted in the frame attached to the transverse member, the lower portion of the side members being extensible or telescopic, bars slidably mounted in the transverse member connected to the extensible portion of the side members, spindles journaled in the frame and arranged transverse to each other, gears connecting the spindles, endless chains operated by the spindles, and means connecting the endless chains to the rods of the side members and the bars of the transverse member.

100 110 115 In testimony whereof I affix my signature in the presence of two witnesses.

IWAN OSTAFIJCHUK.
